UNITED STATES PATENT OFFICE.

HERBERT BELL, OF EAST BOSTON, MASSACHUSETTS.

COMBINATION BEER-COCK.

1,020,8...

Specification of Letters Patent. Patented Mar. 19, 1912.

Application filed July 2, 1909. Serial No. 505,716.

To all whom it may concern:

Be it known that I, HERBERT BELL, a citizen of the United States, residing at East Boston, in the county of Suffolk, State of Massachusetts, have invented certain new and useful Improvements in Combination Beer-Cocks; and I do hereby declare the following to be a full, clear, and exact description of the invention, such as will enable others skilled in the art to which it appertains to make and use the same.

This invention relates to liquid dispensing devices and has special reference to a form of beer cock designed to dispense beer from two different barrels, the cock being arranged so that beer may be drawn from either barrel individually or from both simultaneously.

One object of the invention is to improve the general construction of cocks of this character and to simplify the parts.

With the above and other objects in view, as will be hereinafter apparent, the invention consists in general of a beer cock of improved construction provided with a novel form of plug valve.

The invention further consists in certain novel details of construction and combinations of parts hereinafter fully described, illustrated in the accompanying drawings, and specifically set forth in the claims.

In the accompanying drawings, like characters of reference indicate like parts in the several views, and Figure 1 is a side elevation of a beer cock showing the device assembled. Fig. 2 is a longitudinal section on the line 2-2 of Fig. 1, the parts being arranged for dispensing beer from both barrels simultaneously. Fig. 3 is a similar section showing a part of the device including the plug valve with this valve arranged to dispense beer from one barrel only. Fig. 4 is a vertical section on the line 4-4 of Fig. 2. Fig. 5 is a detail view of the plug valve removed from the cock.

The numeral 10 indicates the body of the device and this body portion may be made as ornamental as desired. Extending rearward from the body portion is a threaded nipple 11 whereon is held a nut 12 for the purpose of securing the cock in the back wall of a bar or other convenient place.

At 13 is indicated the connection that is used to connect the cock to the pipes from the barrels and this connection is provided with branches 14 to one of which is con-

nected one of the pipes leading from the barrels while the other receives the other connection. This connection 13 is joined to the nipple 11 by means of a collar 25, the latter being interiorly threaded and screwed on to the rear end of the nipple, while said collar is retained on said connection against displacement and for rotation for securing the parts together. A partition 15 extends along this connection between the two ends 14 and thus divides said connection into two pipes substantially semi-circular at their forward ends.

Extending vertically through the front end of the body 10 is a frusto-conical bore 16 and running from the back end of the body to this bore is a partition 17 which divides the body of the cock into two pipes. The back ends of these pipes are identical in size and cross section with the front ends of the two pipes in the connection 13 so that when this connection is properly positioned the pipes in the body and nipple form a continuation of the pipes in the connection. These pipes at their forward end are compressed laterally and broadened vertically, as can be seen from reference to the figures showing the sections. From the body 10 projects a downwardly inclined spout 18 and this spout communicates with the chamber 19 formed in the forward end of the valve body opposite the partition 17.

Within the frusto-conical bore 16 is held a plug valve 20 provided with a pair of spaced ports 21, the partition 22 between the ports being the same thickness as the partition 17 and the ports being of identical dimensions with the passages lying on either side of that partition at the forward end thereof. This plug valve is held in the body by means of a nut 23 and is provided with a handle 24.

In the operation of this device let it be assumed that the right hand member 14 has been connected to a barrel of ale and the left hand member to a barrel of porter. Now, if the bartender desires to draw porter, he positions the plug valve 20 so that one of the ports 21 registers with the left hand passage in the valve body leaving the other port 21 blanked off by the side wall of the frusto-conical bore. This will place the plug valve in the position shown in Fig. 3. It will now be observed that the porter can flow from the left hand passage only and will thus be delivered through the

spout 18. If the bartender desires to draw what is commonly known as "half-and-half" he positions the valve as indicated in Fig. 2. Ale will then flow from one barrel and the porter from the other mixing in the chamber 19 and passing out of the spout 18. There has thus been provided a simple and efficient device of the kind described and for the purpose specified.

10 Having thus described the invention, what is claimed as new, is:—

15 1. A combination beer cock comprising a connection having a closed end and a central partition, pipes formed therewith and communicating with separate passages formed by said partition, a casing having a threaded portion exterior thereof and an adjacent shoulder, a nut threaded thereon for securing the casing to a support, a collar 20 detachably connecting the connection to the casing, said casing being provided with a similar partition in line with the first named partition to form separate passages, said casing being further provided with a portion enlarged upwardly and downwardly 25 and terminating in a reduced outlet, said enlarged portion having a vertical bore, and a turning plug operable therein and having a pair of spaced slots forming an intermediate partition adapted to align with the adjacent partition when the valve is opened, said passages in the casing being restricted 30 to align with the slots in the plug which

open into an enlarged circular chamber vertically disposed at the outlet side of the plug.

2. In a beer cock, a casing having a central enlarged portion and an outlet passage extending from said central enlarged portion and being provided with a bore extending transversely of the enlarged portion, a mixing chamber communicating with the bore and with the passage and having curved walls, the space between the curved walls being greater than the diameter of the bore, said casing being further provided with a divided inlet passage, the partition dividing said inlet passage terminating near the bore of the casing, a valve fitted in the bore of the centrally enlarged portion of the casing and provided with two independent passages adapted to shape a liquid flowing through the valve into relatively thin sheets, said valve being so arranged in the casing that one of said sheets will contact with one of the curved walls of the mixing chamber and be deflected thereby across the mixing chamber to intermingle with the other sheet, whereby the two sheets will be intimately mixed.

In testimony whereof, I affix my signature, in presence of two witnesses.

HERBERT BELL.
